UNITED STATES PATENT OFFICE.

THEADORE M. SPURLOCK AND JAMES A. SPRAGUE, OF SITKA, ARKANSAS.

RAILWAY-GATE.

1,383,437.

Specification of Letters Patent.

Patented July 5, 1921.

Application filed July 31, 1920. Serial No. 400,310.

To all whom it may concern:

Be it known that we, THEADORE M. SPURLOCK and JAMES A. SPRAGUE, citizens of the United States, residing at Sitka, in the county of Sharp and State of Arkansas, have invented certain new and useful Improvements in Railway-Gates, of which the following is a specification, reference being had to the accompanying drawings.

10 This invention relates to certain improvements in railway gates and has relation more particularly to a device of this general character wherein a gate member is supported for swinging movement in substantially a horizontal path, and it is an object of the invention to provide a novel and improved mechanism whereby the gate body may be readily and conveniently moved from one position to another, together with 15 means for normally maintaining said gate member in one of its positions.

20 Another object of the invention is to provide a novel and improved railway gate comprising two gate members supported for swinging movement and which are normally maintained substantially in alinement in a direction transversely of the trackway, together with means for moving said gate members in unison into positions at opposite 25 sides of the trackway and in a direction lengthwise of said trackway.

25 The invention consists in the details of construction and in the combination and arrangement of the several parts of our improved railway gate whereby certain important advantages are attained and the device rendered simpler, less expensive and otherwise more convenient and advantageous for use, as will be hereinafter more 30 fully set forth.

The novel features of our invention will hereinafter be definitely claimed.

In order that our invention may be the better understood, we will now proceed to 45 describe the same with reference to the accompanying drawings, wherein:

Figure 1 is a top plan view of a railway gate embodying our invention;

Fig. 2 is an enlarged detail side elevation of a portion of the operating mechanism, and

Fig. 3 is a fragmentary view similar to Fig. 2, but looking at the opposite side of the pillar or column which is positioned to 55 one side of the trackway.

As disclosed in the accompanying draw-

ings, T denotes a trackway having arranged at opposite sides thereof standards or posts 1. Operatively engaged with each of the standards or posts 1 for swinging movement 60 in substantially a horizontal path is a gate member G. The lower portion of each of the gate members G adjacent the coacting standards or posts 1 is provided with an outstanding rock arm 2 extending in a direction away from the gate member, and operatively connected with one of the rock arms 2 is an elongated link 3 disposed in a direction longitudinally of the trackway T and which is also operatively engaged with 70 a rock arm 4 carried by a shaft 5.

The shaft 5 extends transversely of the trackway and is supported in a manner whereby the rock arm 4 has swinging movement in a vertical path as has also a second 75 rock arm 6 carried by the opposite end portion of the shaft 5. The rock arms 4 and 6 are substantially in parallelism and the free end portion of the second rock arm 6 of the shaft 5 is operatively engaged, as at 7, with 80 the lower end portion of a vertically disposed arm 8, said arm being supported, as will be hereinafter more particularly set forth, by the upstanding pillar or column 9 positioned to one side of the trackway T. 85

Also operatively engaged with the lower end portion of the arm 8 is a link 10. The link 10 is operatively engaged with the rock arm 2 of the second gate member. In view of the foregoing it will be seen that as the 90 arm 8 is moved upwardly, the gate members G will be swung in one direction and upon downward movement thereof, said gate members G will be moved in the opposite direction. 95

The pillar or column 9 is provided substantially midway its length with a longitudinally directed slot 11 through which extends a shank 12 carried by the arm or member 8 whereby said arm or member 8 is 100 capable of movement in a direction longitudinally of the pillar or column 9 and is also capable of swinging movement. A face of the pillar or column 9 in close proximity to the upper end of the slot 11 is provided 105 with an outstanding flange or buffer member 14 with which is adapted to contact a buffer member 15 carried by the shank 12 whereby the upward movement of the member or arm 8 is limited. 110

A marginal portion of the arm or member 8 is provided with a rack 16 with which

meshes a cam gear 17 formed on the end portion of a rock lever 18. The lever 18 is supported intermediate its length for rocking movement in a vertical path between the 5 pair of upstanding posts 19.

As the end portion of the lever 18 in operative engagement with the arm or member 8 swings upwardly, said arm or member 8 is also moved upwardly and at the 10 same time the upper portion of said arm or member 8 is swung in a direction away from the lever 18. This swinging movement of the arm or member 8 places under tension a coil spring or other retractile 15 member 20 secured at one end portion to the upper end of the arm or member 8 and at its opposite end portion to the posts 19 whereby said coil spring or retractile member 20 provides means whereby the arm or member 20 is normally maintained at the 20 limit of its inward movement. This member or spring also serves to maintain the racks 16 and cam gear 17 in mesh.

Supported intermediate its ends by the 25 upper end portions of the posts is a horizontally directed arm 21 having one end portion operatively engaged by the links 22 with the end portion of the lever 18 remote from the cam gear 17 thereof so that 30 upon elevation of the opposite end portion of said arm 21, the arm or member 8 will be moved upwardly, resulting in the gate members G moving from their normal position to a position at opposite sides of the 35 trackway T and extending in a direction lengthwise thereof. The normal position of the gate members G is substantially in alignment in a direction transversely of the trackway T.

40 The arm 21 may be operated in any desired manner but it is preferred that the same be moved in a direction to raise the arm or member 8 through electrically operated mechanism and which mechanism may 45 comprise a movable core 23 operatively engaged with the end portion of the arm 21

remote from the links 22 and which core contacts with a solenoid 24. The solenoid 24 is adapted to be energized by the closing of a circuit upon the entrance of a train or the 50 like upon a block arranged in the trackway as is now employed in the various block signaling systems.

From the foregoing description it is thought to be obvious that a railway gate 55 constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement 60 and formation of the several parts herein shown in carrying out our invention in practice except as hereinafter claimed.

We claim:

The combination with a pair of gates supported for swinging movement in a substantially horizontal path, of an arm movably supported adjacent said gate a shank carried by said arm, a stationary arm having a slot extending longitudinally thereof and through which the shank of the movable arm is directed whereby said arm is capable of both endwise and swinging movement, means for imparting upward movement to the movable arm, and means being adapted to return the movable arm to its normal position upon release of said first means, and an operative connection between said arm and the gates whereby the gates are swung toward each other upon movement of the arm in one direction, and away from each other upon movement of the arm in the opposite direction.

In testimony whereof we hereunto affix our signatures.

THEODORE M. SPURLOCK.
JAMES A. SPRAGUE.
